PORTABLE STRUCTURE

Georg Thofehrn and Heinrich Rauchholz,
Berlin, GermanyApplication November 14, 1936, Serial No. 110,912
In Germany November 14, 1935

2 Claims. (Cl. 135—1)

Our invention relates to portable structures such as tent barracks, hangars, and the like.

It is an object of our invention to provide a structure of the kind described, which is easily and rapidly erected and taken to pieces, and which is ready for immediate use when erected.

To this end, we provide a plurality of portal frames which we build up of separable units. The portal frames are equipped with suitable 10 bracing means such as tie rods extending between their bases, and are connected and braced with respect to each other by detachable members, and these members, in turn, are connected and braced by other detachable members, to make 15 upon a structure which is quite rigid although comprising so many components.

The structure is equipped with a fabric which is arranged between the frames, i. e., within the structure.

20 The fabric inside the structure has two advantages. Firstly, the portal frames whose units are normally lattice-work girders, are exposed at the top and the sides of the structure, and break up any flow of air in the longitudinal direction of 25 the structure. Secondly, a gust of wind penetrating into the structure forces the fabric against the portal frames and the bracing members from below and the fabric is efficiently retained.

It is another object of our invention to provide 30 a closure at one end, or at both ends, of the structure which, while affording efficient protection, yet is readily moved out of the way when required.

To this end, we arrange at that end where 35 the curtain is positioned—or at both ends of the structure—a pair of parallel cables which are secured to the structure at their upper, and anchored at their lower ends, for instance, in a suitable sill, and on the two cables we suspend 40 the curtain by means such as annular members which slide on the cables and are secured to the curtain. Halliards are connected to the curtain for raising and lowering it. Obviously, if the structure is so wide that it would be inconvenient 45 to provide a single curtain all over the width, we provide a plurality of curtains of such width that they can be handled conveniently.

Other objects of our invention will appear from the following specification, with reference to the 50 accompanying drawings in which structures embodying our invention, and their details, are illustrated more or less diagrammatically.

In the drawings

Figure 1 is a partial end elevation of the improvement.

Figure 2 is a detail plan view of the same.

Figure 3 is a detail diagrammatic side elevation, illustrating the inside structure of the improvement.

Figure 4 is a detail enlarged side view of a portion of one of the portal frames.

Figure 5 is a detail view of one of the frames.

Figure 6 is a detail central section taken through Figure 5.

Figure 7 is a detail section on the line VII—VII of Figure 6.

Figure 8 is a detail section on line VIII—VIII of Figure 7.

Figure 9 is a section on the line IX—IX of Figure 5.

Referring now to the drawings, and first to Figs. 1 to 5, the structure is equipped with any desired number of portal frames, five of which are shown at 1, 2, 3, 4, 5, in Fig. 5. Each portal frame, as best seen in Fig. 2, has a pair of support units 6 two of which, and four roof-girder units 8, 9, only are shown, it being understood that the units are exactly duplicated at the other side of the frame. The units are connected by any suitable means, not shown, permitting ready assembling and taking to pieces of the portal frames. Such means may be screws or joints of any suitable kind. They have not been shown since they are old in the art.

Obviously, the portal frame may be built up 30 of any desired number of separable units. The size of the individual units is determined by considerations of weight and ease of handling.

By way of example, the units have been shown 35 as lattice-work girders of triangular section, but it is understood that we are not limited to this type of girder.

Preferably, the structure is made of light metal, this term including light-metal alloys, as obviously the components of the structure are easier 40 to handle when of low weight, but again we are not limited to any particular metal or alloy. For instance, steel may be used instead of light metal or alloy.

The lower end of each support 6, is mounted to 45 slide in a base plate, as will be described later, and the two base plates of each portal frame are connected by a tie rod or the like. The upper ends of the supports are held by suitable guys 16 whose upper ends are attached to the supports 50 and whose lower ends are pegged, or otherwise secured, to the ground.

The individual portal frames are connected by detachable longitudinal members or bars 17 which, in turn, are connected by transverse members 18, 55

here shown as tubes. It is understood that the longitudinal members may also be tubular. The connection is shown more fully in Fig. 4. As mentioned, the units are preferably girders of triangular cross-section. Fig. 4 shows that this section is very favorable for connecting the longitudinal bars or tubes 17 to the units. The units are built up of three channelled beams to which the—preferably tubular—lattice bars are riveted or soldered. The two beams at the base of the triangle are equipped with eyes 19 in which hooks 26 at the ends of the longitudinal members 17 are inserted. Similar means, not shown, may be provided as the detachable connection of the transverse members 18 and the longitudinal members 17.

By the means described, we obtain a structure which is quite rigid as its individual components are all positively connected. The components themselves are light and easy to handle, and their connections are simple and readily fastened and unfastened.

In operation, the components of the structure which, as mentioned, may be a hangar for airplanes, are carried to the field on suitable cars. Few cars only are required as the components are light and can readily be stowed on account of their smallness. The cars, due to their light loads, can run on any ground and are not confined to good roads, as heavier cars would be. A definite system is followed in loading the cars, each car carrying the components and strips of fabric for one or more bays of the structure. In situ, each car is driven to the station which corresponds to the position of the parts it carries, in the finished structure. By these means, the erection and taking to pieces of the structure is much expedited.

When the structure has been erected, fabric 31 is hauled up from the ground below the portal frames to immediately below the frames, as will be described. The structure which has been illustrated may be a hangar for airplanes, and the portal frames project freely from the roof and the sides of the hangar and, as mentioned, break up the flow of air along the hangar. As this hangar is rather wide, its curtain is subdivided into five individual curtains, one, 21, at the centre, and two more, 22 and 23, at the left, and other two more, 24 and 25, at the right of the central curtain 21.

The portal frames of this structure will now be described with reference to Figs. 6 and 7.

The lower end of the supports 6 is equipped with a skid mounted to slide in a base plate 26 on a board or other weight-distributing member placed on the ground. The base plate of the opposite support which is quite similar, is connected to the base plate 26 of the support 6 by a tie rod 28.

The side elevation, Fig. 7, shows the skid at the lower end of support 6, and the beams and lattice bars of which the support is built up. It also shows the means for bracing the bays between two supports, being horizontal tie rods 29 at the top and the bottom of the bay, and a pair of diagonals 30.

The fabric 31 is subdivided into webs whose width is equal to the pitch of the portal frames, and normally about 20 feet. The lower ends of the webs are pulled out between the portal frames, and weighted with heaps of sand or other material 54, Fig. 8.

The means for connecting the webs of the fabric and of the curtain or curtains, and the

means for holding, operating and hauling tight the individual webs independently of each other, are similar to those used on sailing vessels, and especially on racing yachts.

Figs. 9 and 10 show the connection of two adjacent webs 31a and 31b. Two leech ropes 32 are sewn to the webs at some distance from their outer edges, and the "lands" thus obtained are turned up to form a sort of flange whose inner end is preferably turned over to afford complete protection against wind and rain. Registering thimbles are inserted in both members of the flange, and lacing 53 is drawn through the thimbles, as shown in Fig. 10. To support the seam at the inner end of the flange, ropes 50 and 51 are sewn to the webs 31a and 31b transversely with respect to their edges and equipped with eyes at their ends through which lacing 52 is threaded. Preferably, several strands of lacing are used to connect the ropes so that the seam can be hauled tight when the connection becomes slack through transverse stretching of the webs.

Two parallel cables 34 and 35 are arranged in each portal frame at opposite sides of its central plane. The cables extend from a bracket 33 at the base of the support 6 through to another bracket at the base of opposite support. This other bracket is quite similar to the bracket 33 and so has not been illustrated. The eyes of the cables are connected to the brackets by lacing 79 threaded through the eyes of the cables, and through holes in the bracket, permitting tight-hauling when a cable has become slack. The leech ropes 32 are connected to the brackets by similar lacing 80, also designed for tight-hauling.

Annular members 36 are secured to each leech rope 32 and placed over the corresponding cable 34 or 35 on which they are free to slide. By these means, the webs are suspended from, and guided on, the cables which are parallel to their edges.

The means for hauling up the fabric 31 will now be described. It should be noted that when the structure has been erected, the cables 34 and 35 are threaded through the annular members 36, the cables and leech ropes are anchored in the brackets 33 at both sides of the structure, and the edges of the webs have been connected as shown in Fig. 9, the fabric lies flat on the bottom of the structure, ready for hauling up.

At the angles of the structure, and at suitable intermediate positions, shackles 37 are suspended which engage about the cables 34, 35 and are connected to suitable halliards, as will now be described. The shackles present ample areas to the cables, preventing wear and damage, and their cable seats are curved in conformity with the curvature of the cables at the angles.

The lowermost shackle 37a is operated by a halliard 38 on a pulley 39 at the upper end of the support 6, the free end of the halliard being clamped, or otherwise secured, at 40a on the base of the support.

Similar means, including a halliard 41, pulleys 43 and 44, and a clamp 40b; and a halliard 42, pulleys 45, 46, and 47, and a clamp 40c; are provided for the intermediate shackle 37b and the topmost shackle 37c, respectively. Obviously, the means which have been described for the left portion of the portal frame, are duplicated for the portion at the right which is not shown.

When the fabric has been hauled up, the cables and leech ropes are hauled tight.

When the fabric has been hauled up, and the

cables and ropes have been hauled tight, the ends of the fabric are pulled out and weighted, as shown in Fig. 8. Gusts of wind have no tendency to lift the fabric from the portal frames, but, on the contrary, force it up toward the inner faces of the frames. When any one of the components becomes slack, re-tighthauling is easy. The lengthening of the fabric and the ropes is about equal, and that of the steel cables 34, 35 is negligible as against that of the fabric and ropes. The rings 36 slide easily on the cables and do not interfere with the tighthauling of the fabric. At the same time, the rings prevent sagging of the fabric.

15 The curtain, or curtains, and the means for hauling up and lowering the curtain, will now be described for one of the subdivisions, 23, of the curtain, it being understood that similar means may be arranged for operating any, or all, of the individual curtains. At its lower end, the curtain 23 is weighted by a yard 55, with pulleys at both ends. A third pulley 57 is suspended from the first portal frame by a wire or the like, 59, Fig. 11. A halliard 60 is attached to the frame at 61, and passes down, about the two pulleys 56 of the yard 55, and then up again to the pulley 57 and to a winch or the like, not shown. When a pull to the left is exerted on the halliard 60, the curtain is hauled up. Less power is required, and 20 the curtain can be hauled up by hand, if the halliard is arranged as follows: From 61, where it is attached to the frame, the halliard 60 descends to the pulley 56 at the right of the yard 55, then ascends to a pulley positioned near the 25 point 61 of attachment, moves horizontally to another pulley above the pulley 56 at the left of yard 55, down to that pulley, and up to pulley 57 whence it is taken out of the structure.

Similar means, not shown, are provided for 30 operating the other individual curtains.

The means for guiding the curtain are similar to those described for guiding the webs of the fabric 31. Two parallel cables are provided, only one of which is shown at 62. Leech ropes 63 are 35 sewn to the curtain near its edges, and rings 64 secured to the leech ropes slide on the corresponding cables. It will appear that this system is quite similar to the web-hauling one, only the brackets 37 on the webs are replaced by the yard 55 at the lower end of the curtain 23.

Each cable 62 has an eye at its upper, and another eye at its lower end. The upper end of each cable is suspended from the portal frame by wires or the like 65, and its lower end is connected to a shackle 67, 68 which is anchored in a sill 66 by a stone bolt 69. Each leech rope is connected to a stone bolt 71 in the sill 66 by a detachable ring 72.

At its upper end, the curtain 23 is tightly connected to the fabric 31. A strip 13 is attached to the fabric from below near its end, and this strip is connected at its lower end to a turned-over portion at the upper end of the curtain by lacing such as 55 in Fig. 10. The end of the fabric covers the strip connection with an extension. The extension is, at its lower end, connected to a flap 74 on the curtain by a suspension member

75. The extension is supported by a member 76 whose upper end is secured to the portal frame. By these means, a tight connection is effected at the upper end of the curtain.

When it is desired to haul up the curtain, the rings 72 which hold the leech ropes 63 are removed, and the halliard 60 is pulled by hand, or by a winch. If the width one of the individual curtains lays open between the cables 62, is sufficient for admitting the air plane or the like which is to leave or to enter the hangar, the cables 62 are left as they are. If, however, a wider clearance is required, one of the cables 62 is detached from its anchoring point at the sill 66, and the adjacent cable of the curtain at one side, or the other side, of the curtain which has been hauled up, is also detached. The two cables are then connected by a halliard, not shown, which moves about a pulley at the upper end of a support 6 or 7. By pulling this halliard, the two cables which have been detached, are hauled up together.

The weighting of the fabric by sand, as shown in Fig. 8, would not be convenient with respect to the curtains. Therefore, we arrange a wind guard in the shape of a board or flap 77 which is hinged to the front edge of the sill 66 at 78. The free end of the wind guard 77 is preferably cut out for the cables 34, 35. When the curtain has been lowered, the wind guard is turned up 30 and placed against the curtain with its upper end. When it is desired to haul up the curtain, the guard is turned down and laid flat on the ground. The guard will perform its function of deflecting the flowing air in upward direction without its 35 free end being cut out.

We claim:

1. In a portable structure of the kind described, separable units of light construction making up a plurality of portal frames, a fabric suspended within the structure in the immediate vicinity of the portal frames, bracing means connecting the bases of each portal frame, members detachably connected to the portal frames and to each other, for bracing the portal frames with respect to each other, end portals at the ends of the structure, each end portal supporting a plurality of curtains, and cables anchored to the structure and to the ground for guiding the individual curtains.

2. In a light-metal portable structure of the kind described, a plurality of portal frames built up of separable units of triangular cross section, each portal frame comprising a pair of members each consisting of a support and a roof girder including an obtuse angle, the two members being arranged to be connected by the inner ends of their roof girders, so that such roof girders include an obtuse angle at the center of the frame, members detachably connected to the portal frames and to each other, for bracing the portal frames with respect to each other, and a fabric suspended within the structure in the immediate vicinity of the portal frames.

GEORG THOFEHRN.
HEINRICH RAUCHHOLZ.
